UNITED STATES PATENT OFFICE.

KESTER J. PEERS, OF BOSTON, AND ARTHUR L. CURRIER, OF NEWTON, MASSACHUSETTS;
SAID CURRIER ASSIGNOR TO SAID PEERS.

CUTTER FOR FIBER NEEDLES.

1,161,154.

Specification of Letters Patent. Patented Nov. 23, 1915.

Application filed August 28, 1914. Serial No. 859,133.

To all whom it may concern:

Be it known that we, KESTER J. PEERS, of Boston, in the county of Suffolk and State of Massachusetts, a subject of George V, King of Great Britain and Ireland, and ARTHUR L. CURRIER, of Newton, in the county of Middlesex, in said State, a citizen of the United States, have invented a new and useful Improvement in Cutters for Fiber Needles, of which the following is a specification.

The use of fiber needles for talking machines is increasing and as each needle loses its point with one use and so can be used satisfactorily but once unless it is retrimmed, a demand for cutters to trim such needles has arisen. These needles as is well known are triangular in cross section and are trimmed to a point in a plane at an angle to their length so that the point is a continuation of one of the angular edges.

The present invention is an improvement on a cutter described in an application for Letters Patent of the United States, Serial No. 809,207 filed by the said Peers, December 29, 1913. The shear cut referred to in that application has been found advantageous and the means of holding the needle during the cutting operation so that its pointed edge will not be jammed has also been found to be practically necessary and this present invention relates to improved means for securing these results together with other features which go to make up a practical cutter which is convenient and effective, and also lends itself to inexpensive construction because its parts may be made by dies.

Our invention will be understood by reference to the drawings in which—

Figures 1 and 2 are front and rear elevations of a cutter embodying our invention in its preferred form. Figs. 3 and 4 are side elevations of the cutter taken from opposite sides. Fig. 5 is a top view of the cutter, and Fig. 6 is a section on line 6—6 of Fig. 1. Fig. 7 is a vertical section of the device. Figs. 8 and 9 are details of the two levers on which the operative parts are mounted. Figs. 10 and 11 are modifications of the opening through which the needle is fed. Figs. 12 and 13 are modifications of the cutting blade, and Figs. 14 and 15 show modifications of the needle clamp.

The device comprises two handle levers

pivoted together, their lower ends being spring-controlled handles and their upper ends carrying the operative parts. The handles of the levers are marked A and B, respectively, and the plate or upper part of each lever which carries the working parts is marked A¹ and B¹, respectively. Each handle also carries an attaching plate a, b, which interlocks with the shanks which connect the handles B and A with the plates B¹ and A¹. A screw pin C passes through these four parts, namely, the shanks referred to and the parts a and b to form a fulcrum for the levers, a nut c fitting the end of the screw and acting as a lock nut. A tongue D having a suitable eye through which the pin C also passes and arms d at its lower extremity engages two springs d¹, one pressing against a boss d² on each handle so as to keep the handles normally separated.

The plate A¹ carries the means for holding and presenting the work to the cutter by means comprising a work support and a clamp together with an opening through which the work is fed. The work support is marked E and comprises a trough angular in cross section open at each end and open at one side, its opposite angle retaining the appropriate edge of the needle, namely, that which carries the point. This work support, it will be noted, is at an angle to the plate A¹ and at its junction with plate A¹ is an opening e which is a projection of this trough so that the needle may pass through the plate and reach the cutting blade. For this purpose the opening is preferably substantially the shape of the lower or pointed end of the needle but it has an elongated recess e¹ in one corner as and for the purposes described in the said application, namely, to prevent the jamming of the needle when engaged by the cutter, the cutter pressing the needle against the upper side of the triangular opening, the other walls of the triangular opening serving to keep the needle from lateral movement and the elongated recess e¹ being located to relieve the point forming edge of the needle from pressure. This means is preferably extended into the trough.

We have shown in Figs. 10 and 11 other means for accomplishing this. In Fig. 10 it will be noted that the opening e² is four-sided, the upper side being at an appropri-

ate angle to receive the corresponding side of the needle which is marked α and is shown in cross section, a pin e^3 being attached to the plate A^1 to retain the needle in proper position. In Fig. 11 a similar construction is shown wherein, however, instead of a pin e^3 a tongue e^4 is provided, this tongue forming part of a plate A^2 which we prefer to use to form a face for the plate A^1 , this plate A^2 being constructed of hard steel and being riveted or otherwise suitably attached to the inner face of the plate A^1 .

To clamp the needle in the support E we provide a lever F pivotally mounted on the outside of the plate A^1 (Fig. 1) by a pin or fulcrum f . The lever F has at its upper end a finger f^1 provided preferably with a serrated edge on its inner face adapted to be moved toward the support E and close the open side thereof. It should be somewhat yielding preferably because its function is to press the needle into the support

and hold it firmly during the cutting operation, and as the needles vary somewhat in size it should have sufficient movement to hold the smallest needle in place. The serrations on the face of this finger f^1 should be such as to hold the needle down against the cutting blade and prevent its being drawn inward by the pulling tendency of the cutting blade. In order to throw this lever F at the proper time we give to the edge of the plate b a cam shape providing it with a recess f^2 to receive the hook f^3 at the lower end of the lever. It will be noted from Fig. 1 that when the handles are brought together the lower end of the lever F will be pressed outward and the hook f^3 will be thrown out of the recess f^2 . When the handles are released, however, the reverse operation will take place, the edge of the recess engaging the hook f^3 and drawing the lever back into place and releasing the needle.

We have shown other means of operating the finger f^1 in Figs. 14 and 15. In Fig. 14 the lower end of the lever rests upon the edge of the plate b which in this case has no recess but is shaped to throw the upper end of the lever into the trough or holder E , the return movement being caused by a spring f^4 attached to the plate A^1 .

In Fig. 15 the finger is mounted on a yoke frame having two arms f^5 which in like manner are operated by the edge of the part b .

In addition the plate A^1 has an overhanging lip G to form a guide for the plate B^1 and to hold the plates in facial contact, and it is also provided with a notch a^1 to co-act with the projection b^1 on the plate B^1 to limit the cutting movement of the parts. The lip G also serves as a stop to engage a projection b^2 on the part B^1 so as to limit the expansive movements of the springs d^1 .

The plate B^1 carries a cutting blade H which is pivoted thereto by a pin h , the pin simply serving as a fulcrum for the blade which is a lever and not being headed in order to allow the blade to be removed for sharpening. The blade H is also slotted as at h^1 and this slot co-operates with a pin h^2 on the part A^1 . The slot is preferably straight and as the pin h^2 moves in the arc of a circle about the fulcrum C it drives the plate upward at the proper time causing it to pass the opening through which the needle projects. Thus the blade makes a shear cut across the end of the needle. This same result may be secured in other ways, for example, as shown in Figs. 12 and 13, where the blades H^1 , H^2 are riveted to the part B^1 . In Fig. 12 the blade H^1 has a curved cutting edge, the curve being eccentric to the movement of the part B^1 so that as the parts pass each other the same shearing operation is secured.

In Fig. 13 a blade H^2 having a straight edge is used, the width of the blade and its location being such that as the part B^1 swings up to perform the cutting operation it, as it were, pushes the blade upward across the needle.

The projection b^2 which serves as a stop with the part G also is so located on the plate B^1 as normally to lie opposite the opening E through which the needle is fed for cutting and hence it serves as a stop or guide to determine the amount of material to be cut from the needle.

In practice the needle is pushed into the support until its end reaches this part b^2 and immediately upon gripping the handles although this part b^2 moves out of the way the finger f^1 on the lever F engages the needle so that it will remain in its proper position to be trimmed.

We believe from the above description that the operation of this device will be clearly understood and we also believe that it will be understood that modifications as to the details of this construction may be had without departing from the spirit of this invention as we do not mean to limit ourselves to the exact construction shown.

What we claim as our invention is:

1. In a device of the kind described, two handle levers pivoted together, one of said handle levers having a needle support and the other handle lever having a cutting blade, and means operated by the movement of said handle levers and having a movement relative to said support to co-operate with the latter to clamp a needle thereon when the cutting blade is to operate to trim a needle.

2. In a device of the kind described, two handle levers pivoted together, one of said handle levers having a needle support and the other handle lever having a cutting

- blade, and yielding means operated by the movement of said handle levers and adapted to coöperate with said needle support to clamp a needle thereon.
- 5 3. In a device of the kind described, two handle levers pivoted together, one of said handle levers having a needle support and the other handle lever having a cutting blade, and means adapted to coöperate with
- 10 10 said needle support to support a needle therein, said means comprising a clamping lever and means operable with the operation of said handle levers to move the end of said clamping lever into said holder.
- 15 4. In a device of the kind described, two handle levers pivoted together, one of said handle levers having a needle support and the other handle lever having a cutting blade, and means adapted to coöperate with
- 20 20 said needle support to support a needle therein, said means comprising a clamping lever and means operable with the operation of said handle levers to move the end of said clamping lever into said holder, and
- 25 25 means to withdraw it therefrom to release the needle.
5. In a device of the kind described, two handle levers pivoted together, one of said handle levers having a needle support and
- 30 30 the other handle lever having a cutting blade, and means adapted to coöperate with said needle support to support a needle therein, said means comprising a clamping lever mounted upon the handle lever car-
- 35 35rying said needle support and a cam mounted on the other handle lever and adapted to engage said clamping lever and operate it.
6. In a device of the kind described, two handle levers pivotally connected, a work
- 40 40 support mounted on one of said handle levers and terminating in an opening through said lever through which a needle may project, and a cutter blade mounted on the other handle lever, and means whereby said
- 45 45 blade may have a movement across said opening eccentric to the pivot of said handle

levers, said means comprising a pivot whereby said blade is connected to one of said handle levers, a slot in said blade and a pin engaging said slot and connected to 50 the other handle lever.

7. In a device of the kind described, two handle levers pivotally connected, one of said handle levers carrying a work support and the other a cutting blade adapted to cut 55 a needle supported by said work support, a gage mounted on the blade carrying handle lever normally in register with the work support, and means carried by said work-support-carrying handle lever adapted to 60 engage said gage and limit the movement of said handle levers in one direction.

8. In a device of the kind described, two handle levers pivotally connected, and means for keeping their handle ends normally separated, one of said handle levers carrying a work support and the other a cutter blade and stops mounted on each lever near the outer end thereof, one located to limit the cutting movement of the parts 70 and the other to limit the expansive movement of the springs.

9. In a device of the kind described, two handle levers pivotally connected, one of said handle levers carrying a cutter blade 75 and the other carrying a work support, said work support terminating in an opening in its handle lever, said opening having a flat side and said cutter blade being located on its handle lever to force the flat side of a 80 needle against said flat side of said opening during the cutting operation, and means forming part of said opening to engage another flat side of said needle to hold it against lateral movement during the cutting operation without engagement of a 85 corner edge thereof.
